UNITED STATES PATENT OFFICE.

NATHAN D. INGRAM, OF BROOKLYN, NEW YORK.

DESIGN FOR AN UMBRELLA-RUNNER OPERATOR.

SPECIFICATION forming part of Design No. 34,480, dated May 7, 1901.

Application filed April 1, 1901. Serial No. 53,957. Term of patent 14 years.

To all whom it may concern:

Be it known that I, NATHAN D. INGRAM, a citizen of the United States, residing at Brooklyn, in the county of Kings and State of New York, have invented and produced a certain new and original Design for Umbrella-Runner Operators, of which the following is a full, clear, and exact description.

This invention relates to a sliding tube or operating device for umbrella-runners; and the object of the invention is to produce a new form or configuration of the said device.

The invention consists of a runner-operating device composed of two hollow cylindrical bodies with interposed converging slopes and each having a terminal slope.

In the accompanying drawings, illustrating my invention, Figure 1 is an elevation, and Fig. 2 is a longitudinal section.

The leading feature of my design is the four

slopes or sloping walls, respectively, occurring two in the center and one at each end of the device. There are two hollow cylindrical portions, between which are the two converging slopes, and each portion has an end slope, one 25 sloped end larger than the other, and the smaller end being provided with a beaded and milled terminal.

The design is applicable for runners not only of umbrellas, but also those of parasols 30 and like structures.

What I claim is—

The design for an umbrella-runner operator, substantially as shown and described.

In testimony whereof I have hereunto set 35 my hand this 27th day of March, A. D. 1901.

NATHAN D. INGRAM. [L. S.]
